UNITED STATES PATENT OFFICE.

THEODORE L. FOUST, OF TERRE HAUTE, INDIANA.

PATIENT-HANDLING APPARATUS FOR BEDS.

1,312,439.

Specification of Letters Patent.

Patented Aug. 5, 1919.

Application filed April 12, 1917. Serial No. 161,560.

To all whom it may concern:

Be it known that I, THEODORE L. FOUST, a citizen of the United States, residing at Terre Haute, in the county of Vigo and State of Indiana, have invented a new and useful Patient-Handling Apparatus for Beds, of which the following is a specification.

This invention relates to apparatus for handling patients, and includes certain features forming a part of the structure disclosed in Patent No. 1,197,731, issued to me on September 12, 1916.

One of the objects of the invention is to provide means whereby the sheet on which the patient is resting can be fastened to an elevator so that by actuating the elevator the patient can be lifted bodily from the mattress.

20 A further object is to provide elevating or handling means which can be shifted to turn the patient without requiring any effort on the part of the patient.

A still further object is to provide handling mechanism which can be easily actuated, is compact and durable and is efficient in operation.

With the foregoing and other objects in view which will appear as the description 30 proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

40 In said drawings:—

Figure 1 is a side elevation of a bed having the present improvements combined therewith.

Fig. 2 is an end elevation thereof.

45 Fig. 3 is a central vertical section through a portion of one of the segments and adjacent parts.

Fig. 4 is a section on line 4—4 Fig. 3.

Referring to the figures by characters of 50 reference 1 designates a bed structure and secured to the head and foot of the bed at the centers thereof are elongated guide housings 2 preferably formed of channel strips having their open faces extended inwardly.

55 The upper and lower ends of these open faces are closed by attaching strips 3 extend-

ing upwardly and downwardly from the strips and secured to the bed structure.

Slidably mounted within each of the 60 housings 2 is a bar 4 a portion of which is provided with rack teeth 5. Extending from each bar and projecting from the open 65 face of each housing 2 is a stud 6 on which is pivotally mounted a segment 7 extending throughout the greater portion of the width 70 of the bed and which segment may have openings 8 therein near its ends. These segments are located directly opposite each other and are adapted to swing freely from their supporting studs. The studs fixed on 75 the bars are limited in their downward movement by the housing.

Journalized upon the head and foot of the bed is a longitudinal shaft 8' having gears 9 which engage the teeth 5 on the two bars 75 4. A ratchet wheel 10 is secured to this shaft and is normally engaged by a pawl 11 mounted on one end of the bed.

A sprocket 12 is secured to shaft 8' and is engaged by a chain 13 adapted to receive 80 motion from a sprocket 14 secured to a shaft 15. This shaft is journalized in a bracket 16 secured to one end of the bed and a gear 17 is secured to said shaft and meshes with another gear 18 which, in turn, is secured to a 85 drive shaft 19 journalized in the bracket 16. Any suitable means, such as a crank arm 20 may be provided for rotating the shaft 19.

It is to be understood that under ordinary 90 conditions, the segments 7 hang freely from their pivot studs 6. When a patient is to be raised the sheet on which the patient is resting is drawn tightly at its ends about the respective segments 7 and fastened to said segments in any manner desired. For example, tapes or other fastening means can be extended through the openings 8 and tied about the sheet. After the sheet has thus 95 been secured, the shaft 19 is rotated so that motion will be transmitted to shaft 8' and the gears 9 cause the rack bars 4 to move upwardly. Therefore the segments will also be carried upwardly and will lift the patient from the mattress. While the patient is thus supported, the segments 7 can be swung 100 105 on their supporting studs, thus to turn the patient from one side to the other, and after the patient has been turned, the segments can be lowered so that the patient will be replaced on the mattress.

What I claimed is:—

1. Apparatus of the class described in-

cluding a bed structure, guide housings connected to the ends of the bed, members slidably mounted within the housings, studs thereon and limited in their downward movement by the housings, segments pivotally connected to the studs, and means for simultaneously raising and lowering said members, said means including a shaft journaled on the ends of the bed structure, gears 10 upon the shaft engaging the respective slideable members, an operating shaft below the said gears and within convenient reach of the operator, and means for transmitting motion from said operating shaft to the gear shaft.

2. The combination with a bed structure, of channel strips secured to the ends of the structure and having their open faces pre-

sented inwardly, attaching strips secured within the end portions of the channel 20 strips and attached to the bed structure, bars slidably mounted within the channel strips and projecting upwardly therefrom, studs extending from the respective bars and projecting between and limited in their downward movement by the attaching strips, segments pivotally connected to and movable with the studs, and means for sliding the bars.

In testimony that I claim the foregoing as 30 my own, I have hereto affixed my signature in the presence of two witnesses.

THEODORE L. FOUST.
